SYNCHRONIZING DEVICE FOR MUSICAL INSTRUMENTS OR OTHER APPARATUS

Application filed January 24, 1928, Serial No. 249,136, and in France January 27, 1927.

The present invention relates to a device intended for synchronizing with one another several apparatus, more particularly musical instruments driven mechanically, pneumatically or electrically, the operation of which is controlled by sheets or rolls of perforated paper. This device is characterized by the fact that special perforations, formed in the sheets or rolls of perforated paper determining the operation of the different apparatus, act upon relays or intermediate members, which control contacts arranged in such a manner that when synchronism is broken between one of the apparatus, regarded as a conductor apparatus, and one or other of the conducted apparatus, these contacts act upon a member regulating the speed of the motor driving the corresponding conducted apparatus, in such a way as to restore synchronism.

For example these special perforation control, by means of tracker bars, sets of diaphragm relays or "valves", corresponding to the conductor apparatus and to each of the conducted apparatus, and actuating in their turn electrical contacts included in the circuits of the means for regulating the speed of the motors driving the corresponding conducted apparatus, the valves corresponding to each apparatus conducted being arranged in such a way as to act in an opposite sense to the valve corresponding to the conductor apparatus, so as to close the circuit of the regulating means only when there is not synchronism between the conducted apparatus in question and the conductor apparatus.

The motor driving the conductor apparatus is adjusted to the desired speed and the motors of the conducted apparatus are adjusted to a slightly higher speed, and the means for regulating the speed of the motor driving each of these conducted apparatus consists of an electromagnetic brake acting upon the shaft of this motor and included in a circuit controlled by the contacts actuated by the valves corresponding to the conductor apparatus and the valves corresponding to the conducted apparatus in question, in such a way as to retard the movement of this conducted apparatus when there is not synchronism.

nism between the latter and the conductor apparatus.

Preferably the special perforations, in the sheets or rolls of perforated paper controlling the operation of each of the apparatus to be synchronized, are constituted by series of perforations of identical length each comprising a number of perforations equal to the number of the relay valves to be actuated, the corresponding perforations of the different series being arranged in alignment in such a way as to pass in front of the same holes in the tracker bar and at the same distance from one another, while the adjacent perforations of each series are offset longitudinally in relation to one another by the length of these perforations, in such a way that one perforation begins to uncover a hole in the tracker bar at the moment when the preceding perforation leaves the corresponding hole in this tracker bar, the length of these perforations depending upon the accuracy to be obtained in the synchronization.

The accompanying drawings represent by way of example one form of carrying out the invention.

Figure 1 shows the roll of paper provided with the special perforations.

Figures 2 and 3 are views in front and side elevation respectively of this roll of paper passing in front of the tracker bar, constituting the controlling means for the mechanism of the apparatus to be synchronized.

Figure 4 is a view in section of a set of pneumatic relays or "valves" controlled by the special perforations of one of the apparatus to be synchronized, namely, the conductor apparatus.

Figure 5 is a corresponding view of a set of pneumatic relays or "valves" controlled by the special perforations of another of the apparatus to be synchronized namely, the conducted apparatus.

Figure 6 is an external view of the whole of the synchronizing device in the case of two sets of apparatus.

Figure 7 is a diagrammatic view illustrating the synchronizing arrangement of the component part and circuits of the apparatus

where a plurality of conducted apparatuses are to be synchronized with a conductor.

As represented in Figure 1, the roll of perforated paper P, controlling the operation of one of the apparatus to be synchronized, comprises special perforations arranged near one of the edges of the sheet of paper; these perforations, which are all of the same length, are arranged in series of three holes a b c, a' b' c', a'' b'' c''; the corresponding perforations in the different series (a a' a'', b b' b'', c c' c'') are arranged in alignment in such a way as to pass over the same holes in the tracker bar; they are likewise situated at the same distance apart.

Moreover, in each series of perforations, the perforations are offset longitudinally by a distance equal to the length of the perforations. It follows that at the moment when 20 any one of these special perforations leaves the corresponding hole in the tracker bar, the next perforation of the series or of the following series begins to uncover another hole in this same tracker bar. The length of 25 these perforations, or distance d between successive perforations, depends upon the accuracy to be obtained in the synchronization; if for example, the roll travels at a speed of 2.7 m. per minute, that is 45 mm. per second, 30 and if it is desired to attain an accuracy of the order of 1/15th of a second, the perforations will have a length of 3 mm.

When the roll of perforated paper P unwinds (Figures 2 and 3), these special perforations pass over the corresponding special holes 1, 2, 3, formed in the tracker bar; these holes are of number equal to that of the perforations in each series, that is to say to the number of three in the example considered; the perforations a a' a'' will pass over the hole 1, the perforations b b' b'' over the hole 2, and the perforations c c' c'' over the hole 3. Each of these supplementary holes in the tracker bar is connected by a tube 40 k to a pneumatic relay which will be designated in the present description under the name of "valve", by analogy with the pneumatic valves employed in pneumatic musical instruments.

50 The set of these relays or pneumatic valves S¹ S² S³ corresponding to the conductor apparatus is represented in Figure 4; each of the valves in this set is of the same construction. A light diaphragm e divides the internal capacity delimited by the valve box into two chambers; the upper chamber which communicates through the tube h with the corresponding hole in the tracker bar F, and through the hole g, provided with a capillary orifice g¹, with the bellows or other apparatus S producing suction; the lower chamber communicates with the atmosphere through the hole h. To the diaphragm e is fixed a small pad e¹ attached to a metal rod e² carrying a member e³ intended to come

into contact with a screw i passing through the bottom of the valve box. The metal rod e² passes through a hole formed in a metal plate j which is connected electrically by a conductor j¹ to the rod e² and which carries outside the valve a terminal j². A conductive metal plate i¹ carrying a terminal i² supports the screws i corresponding to the valves S¹ S² S³ of the conductor apparatus set. When the holes (1, 2, 3) of the tracker bar 75 F are not uncovered by the special perforations in the paper roll P, the diaphragm e is lifted in each valve S¹ S² S³, for it is subjected upon its upper face to the suction in the bellows S, whereas the atmospheric pressure makes itself felt upon its lower face through the orifice h; in these conditions contact is interrupted between the screw i and the member e³.

On the other hand when a hole (1 or 2 or 3) 85 of the tracker bar F is opened by one of the corresponding special perforations (a a' a'', or b b' b'', or c c' c''), in the corresponding valve (S¹ or S² or S³), the atmospheric pressure makes itself felt upon the upper and 90 lower faces of the diaphragm e, through the tube k and through the orifice h; so that under the influence of gravity, the diaphragm falls and contact is established between the screw i and the member e³.

95 The second apparatus, or conducted apparatus, to be synchronized with the first, comprises likewise a set of valves s¹ s² s³ (Figure 5) which are arranged in an inverse manner to the foregoing. The diaphragm l is likewise connected by the intermediary of a pad l¹ and a metal rod l² to a contact member l³; but this rod l² passes through a contact blade n adjustable in position by means of a screw 100 n¹. Contact is established between member l³ and blade n when the diaphragm l occupies its raised position, that is to say when the corresponding hole in the tracker bar F corresponding to this conducted apparatus is closed, that is to say when the suction at the 110 bellows s corresponding to this conducted apparatus makes itself felt upon the upper face of the diaphragm l, while the lower face of the latter is subjected to the atmospheric pressure.

115 In each of the valves s¹ s² s³, the metal rod l² passes through a conductive plate o, which is connected electrically by the conductor o¹ to this rod l² and which carries outside the valve a terminal o². Another terminal n² 120 is fixed upon a conductive plate n³ carrying the adjusting screws n¹ of the contact blades n.

125 In the general view represented in Figure 6, M designates the pneumatic (or electric) motor driving the roll of perforated paper P of the conductor apparatus (on the right of the figure); the special perforations in this roll P, passing in front of the corresponding 130

holes of the tracker bar F, control the valves S¹ S² S³.

- 5 m designates the pneumatic (or electric) motor driving the roll of perforated paper p of the conducted apparatus (on the left of the figure) to be synchronized with the former; the special perforations of this roll p passing in front of the corresponding holes of the tracker bar f control the valves s¹ s² s³.
 10 10 The shaft of this motor m is connected by a speed reducing gear m¹ m² m³ to a wheel r, which may be braked by a shoe u carried by the armature u¹ of an electromagnet t, arranged in a circuit controlled by the contacts 15 of the valves S¹ S² S³, s¹ s² s³.

- 20 As represented in Figure 6, conductors connect together in pairs the terminals j² o², that is to say the contact members e³ l³ belonging respectively to the valves S¹ and s¹, S² and s², S³ and s³; on the other hand, the terminal i² (that is to say the contact screws i of the valves S¹ S² S³) as well as the terminal n² (that is to say the contact blades n of the valves s¹ s² s³) are connected to the exciting 25 coil of the electromagnet t.

- 30 When synchronization is established between the conductor apparatus and the conducted apparatus, and when the special perforations of the rolls P and p corresponding to these 35 apparatus pass at the same time in front of the holes in the corresponding tracker bars F and f, contact is closed between the contact members e³ and i of the valves S¹ S² S³ corresponding to the hole uncovered in the tracker bar F, in the set of valves of the conductor apparatus; on the other hand, contact is broken between the members l³ and n of the valves s¹ s² s³ corresponding to the uncovered hole in the tracker bar f, in the set of valves 40 s¹ s² s³ of the conducted apparatus. It follows then that the exciting circuit of the electromagnet t is not closed and that there is no braking of the motor m of the conducted apparatus.

- 45 The motor m driving the roll p of this conducted apparatus is adjusted to run at a speed slightly greater than that of the motor M of the conductor apparatus; hence the movement of the roll p of this conducted apparatus tends to accelerate. In these conditions, at a given moment, one of the supplementary holes in the tracker bar F of the conductor apparatus will be uncovered by a special perforation in the roll P, whereas the 50 corresponding hole in the tracker bar f of the conducted apparatus will be already covered again by the roll p. Contact will therefore be established at the same time between the members e³ and i of the corresponding valve 55 of the set belonging to the conductor apparatus, and between the members l³ and n of the corresponding valve of the set belonging to the conducted apparatus. The electromagnet t will be excited and will attract its 60 armature u¹ so that the brake shoe u will

brake the wheel r and the motor m will tend to be stopped until the moment when the two corresponding special perforations in the rolls P and p of the conductor apparatus and conducted apparatus pass together in front of the supplementary holes of the tracker bars F and f. There will therefore be a succession of brake actions, the rapidity and the closeness of which are such that there is established, for the motor m driving the roll p of the conducted apparatus, a working speed lower than that which this motor m would assume if it were not synchronized, but which is equal to that of the motor M of the conductor apparatus, which is adjusted in such a way as to obtain the performance of the piece of music at the desired tempo.

65 In the case where there are several conducted apparatus to be synchronized with one conductor apparatus, the arrangement will be the same as shown in Figure 7; the circuits of the electromagnetic brakes u acting upon the motors m of the conducted apparatus will be mounted in parallel; the exciting coil of each electromagnet t will be connected on the one hand to the terminal i² connected to one of the contact members of each of the valves of the set of valves S¹, S², S³ of the conductor apparatus and on the other hand to the terminal n² connected to one of the contact members of each of the valves s¹, s², s³ of the set of the conducted apparatus considered. The other terminals j² o², that is to say, the second contact members of the corresponding valves of the two sets of valves S¹, S², S³ and s¹, s², s³ of the conductor and conducted apparatus, will be connected in pairs, as represented in Figure 7.

70 It is to be understood that this form of carrying out the invention has been given only by way of example and that without departing from the scope of the appended claims, there may be applied thereto a large number of detail modifications.

75 What we claim is

1. A synchronizing device for musical instruments and other apparatus controlled by a perforated sheet, said device comprising a conductor apparatus, a motor driving the same, a number of conducted apparatus, a motor driving each of said conducted apparatus, means for regulating the running speed of each said last mentioned motors, a set of pneumatically operated relay means for the conductor apparatus and each of the conducted apparatus, a tracker bar associated with each of said conductor and conducted apparatus, a perforated sheet associated with each tracker bar and provided, in addition to the usual perforations controlling the operation of the respective apparatus, with auxiliary perforations adapted to cooperate with the respective tracker bar to actuate the said relay means, and to control thereby the speed regulating means of each 80 85 90 95 100 105 110 115 120 125 130

of the motors driving the respective conducted apparatus, for the purpose described.

2. A synchronizing device for musical instruments and other apparatus controlled by a perforated sheet, said device comprising a conductor apparatus, a motor driving the same, a number of conducted apparatus, a motor driving each of said conducted apparatus, electrical means for regulating the running speed of each said last mentioned motors, a set of pneumatically operated relay means for the conductor apparatus and each of the conducted apparatus, a tracker bar associated with each of said conductor and conducted apparatus, a perforated sheet associated with each tracker bar and provided, in addition to the usual perforations controlling the operation of the respective apparatus, with auxiliary perforations adapted to operate with the respective tracker bar to actuate the said relay means, and to control thereby the speed regulating means of each of the motors driving the respective conducted apparatus, each of the relay means comprising contact members, connected in the electrical circuit of the electrical regulating means of the running speed of the motor driving the respective conducted apparatus, for the purpose described.

3. A synchronizing device for musical instruments and other apparatus controlled by a perforated sheet, said device comprising a conductor apparatus, a motor driving the same, a number of conducted apparatus, a motor driving each of said conducted apparatus, electrical means for regulating the running speed of each said last mentioned motors, a set of pneumatically operated relay means for the conductor apparatus and each of the conducted apparatus, a tracker bar associated with each of said conductor and conducted apparatus, a perforated sheet associated with each tracker bar and provided, in addition to the usual perforations controlling the operation of the respective apparatus, with auxiliary perforations adapted to cooperate with the respective tracker bar to actuate the said relay means, a pair of contact members adapted to be actuated by each of said relay means, the contact members of the conductor apparatus and of each of the conducted apparatus being connected in the electrical circuit of the electrical regulating means of the running speed of the motor driving the respective conducted apparatus, the relay means associated with the conductor apparatus being adapted to actuate its contact members in opposite sense to the relay means of each of the conducted apparatus, and thereby to control the electrical means regulating the running speed of the motor driving the respective conducted apparatus, for the purpose described.

4. A synchronizing device for musical instruments and other apparatus controlled by

a perforated sheet, said device comprising a conductor apparatus, a motor driving the same at the desired speed, a number of conducted apparatus, a motor driving each of said conducted apparatus at a slightly greater speed than the conductor apparatus, electromagnetic braking means for each of said last mentioned motors driving the respective conducted apparatus, a set of pneumatically operated relay means for the conductor apparatus and for each of the conducted apparatus, a tracker bar associated with each of said conductor and conducted apparatus, a perforated sheet associated with each tracker bar and provided, in addition to the usual perforations controlling the operation of the respective apparatus, with auxiliary perforations adapted to cooperate with the respective tracker bar to actuate the said relay means, each of the relay means comprising contact members, connected in the electrical circuit of the electromagnetic braking means associated with the motor driving each conducted apparatus, for the purpose described.

5. A synchronizing device for musical instruments and other apparatus controlled by a perforated sheet, said device comprising a conductor apparatus, a motor driving the same, a number of conducted apparatus, a motor driving each of said conducted apparatus, means for regulating the running speed of each of said last mentioned motors, a set of pneumatically operated relay means for the conductor apparatus and each of the conducted apparatus, a tracker bar associated with each of said conductor and conducted apparatus, a perforated sheet associated with each tracker bar and provided, in addition to the usual perforations controlling the operation of the respective apparatus, with auxiliary perforations adapted to cooperate with the respective tracker bar to actuate the said relay means, and to control thereby the speed regulating means of each of the motors driving the respective conducted apparatus, said auxiliary perforations comprising series of perforations, of the same length, in a number equal to the number of relay means to be actuated, the corresponding perforations of the different series being arranged in alignment in such a way as to pass in front of the same holes of the tracker bar, and at the same distance from one another, whilst the adjacent perforations of each series are offset longitudinally in relation to one another by the length of these perforations, for the purpose described.

In testimony whereof we have signed our names to this specification.

EMILE AUBRY.
GABRIEL BOREAU.
